Primary Examiner — Shawn T Gingrich*Assistant Examiner* — Anehita E. Oribabor(74) *Attorney, Agent, or Firm* — Nitin Kaushik(57) **CLAIM**

The ornamental design for a camera circuit board, as shown and described.

DESCRIPTION

FIG. 1 is a front perspective view of a camera circuit board, showing my new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is a perceptive view showing a usage state thereof; and,

FIG. 10 is a perceptive view showing a usage state.

The broken lines in the drawings illustrate the portions of the camera circuit board, which form no part of the claimed design. The broken lines in the form of a cover on the camera circuit board in FIG. 9 and a cover in FIG. 10 form no part of the claimed design.

1 Claim, 10 Drawing Sheets(56)
